16 Claims. (Cl. 101—153)

The present invention relates to a plate photogravure printing machine wherein the flow of the quantity of ink to the surface of the plate can be regulated.

5 The flow of the quantity of ink generally is regulated in such a manner that between the surface of the plate and the inking roller an accumulation of ink or color is maintained as is necessary in the photogravure printing process, 10 in order that the shallowest and the deepest etched recesses may become completely filled with ink or color.

With photogravure printing machines as for example with copper cylinder machines, where 15 the inking roller is not guided, this slight accumulation of ink is of no importance; however, in the case of plate machines, the accumulation of ink left when the inking roller is lifted off the surface of the plate or when leaving this surface, 20 has a very disadvantageous effect, especially as a consequence of the high rotary speed of the inking roller and inasmuch as the machine is sprinkled with ink when the accumulation of ink gets through between the inking roller and the 25 surface of the plate cylinder. In order to avoid this sprinkling, this accumulation of ink must be removed before the inking roller leaves the surface of the plate cylinder.

This is effected according to the present invention by the fact that towards the end of the inking or color applying position the feed of ink to the accumulation is cut off at just the precisely correct moment prior to complete inking of the plate in order that the thereby isolated ink accumulation will be used up by the required further inking of the plate. By these means the 35 presence of any ink which would otherwise be thrown off, when the inking roller leaves the plate-cylinder, is effectively prevented.

40 According to the present invention the quantity of ink supplied to the inking mechanism is regulated both as to time and quantity by such control of the inking roller or by the provision of means which regulate the flow of ink to the accumulation or bead. By mechanically controlling this means or the inking roller the required proper moment for cutting off the ink supply can be accurately adjusted and maintained so that the bead of ink is used up at the correct 45 moment. Instead of controlling the means to regulate the ink supply or feed, it is also possible to control the inking roller for example by imparting movement to the inking roller towards the regulating means or by varying the circumferential speed of rotation of the inking roller.

The ink supply regulating device and the manner of its control may be of any suitable kind. This ink supply device may for example comprise a wiper roller or a scraper-knife which is actuated by means of a cam and is adjustable during 5 working.

Further means are provided on the one hand to regulate the lift of the device for the regulation of the ink supply, i. e. the thickness of the 10 quantity of the flow of ink, and on the other hand to secure a minimum flow of ink at each movement of the said device for the regulation of the ink supply, i. e. to prevent the said device, especially if same consists of a scraper knife, from 15 touching the inking roller and thereby damaging the latter.

Regulation of the quantity of ink or color fed to the inking roller is necessary in order to control the size of the ink accumulation, which 20 itself depends on the lesser or greater consistency of the ink or color. This regulation is effected by varying the ratio of transformation of the driving rods actuating the device which regulates the ink or color supply, the point at which the ratio of transformation of the driving rods is 25 varied being so chosen, that it is possible to see and observe the inking or coloring zone, i. e. that it is possible to observe the effect of the change on the ink accumulation during the time that the adjustment of the ink or color supply is 30 effected. The point at which the adjustment is made must therefore be situated not on the outside of the machine, but on the inside thereof, and as near as possible to the inking or coloring mechanism. For this purpose a lever which rocks 35 a control cam may be conveniently used, the said cam being adapted to rock the lever, by means of which the regulating device is raised during the period of maximum ink supply.

This regulates or controls the ink or color supply 40 as near as possible to the plate inking zone, because in this case it is not necessary to throttle the ink supply very much before the inking operation is finished, but only to an extent corresponding to the distance of the effective zone of the regulating device from the inking zone, plus that extent necessary to use up the ink accumulation. To achieve satisfactory results, the working zone, the form of the regulating device, and its disposition and mounting are so chosen, that the regulating 45 device does not obstruct a full view of the ink accumulation, in order that the inking zone may be fully visible and thus easily controllable.

As regards the device intended for the purpose 50 of preventing the inking roller being damaged by 55

the scraper-knife, an adjustable stop is provided enabling the minimum distance of the scraper-knife from the inking roller to be adjusted. The adjusting device and the stop are mounted on levers which carry the inking roller, the said levers being adapted to be rocked up and down in order to move the inking roller on to or off the plate-cylinder.

By reason of the fact that the limit-stop for 10 the ink-supply regulating device is mounted on the rockable levers supporting the inking roller, the adjustment of the regulating device relatively to the inking roller always remains the same whether the latter is on or off. This is of im- 15 portance insofar as the inking roller is adapted to be moved on or off the plate-cylinder by hand, in order to permit ink to be fed into the trough and to be thoroughly mixed, without the ink reaching the plate straight away.

20 In order to obtain a uniform and consequently regulatable supply of ink to the inking zone, the surface of the inking roller is preferably made, instead of the usual so called composition material, of such a material which is not subject to 25 change in its diameter or dimensions and is easily wiped, scraped and cleaned, a roller made of steel or other suitable metal or alloy is the most suitable for such a purpose.

In order that the invention may be clearly 30 understood and readily carried into effect reference is made to the accompanying drawings which show diagrammatically and by way of example two constructional forms of inking mechanism in accordance with the present invention 35 and as applied to a photogravure plate printing press.

Figure 1 is a side elevation of inking mechanism according to the present invention as applied to a photogravure plate printing press only so much 40 of the latter being shown as is necessary for the purpose of the present invention.

Figure 2 is a side elevation showing a modified form of inking mechanism also in accordance with the present invention.

45 Figure 3 shows the inking mechanism and the several shafts thereon as developed in one plane.

Referring to Figures 1 and 2 an inking roller is shown at 1 and rotates in the usual manner in an ink trough 2. The roller 1 is rotatably mounted with its shaft 3 in levers 4. The inking roller 1 is driven by means of cog wheels 5 Figure 3 from the shaft of the plate cylinder 6, the latter being mounted on axle 6'. These levers 4 are rockably mounted on a pin or bolt 7 in order to 50 enable the inking roller 1 to be raised into operative position or lowered into inoperative position as well as for the purpose of adjusting its 55 position accurately relatively to the plate-cylinder 6. Raising and lowering of the inking roller 1 is effected by a cam 8, which is mounted rockably on a pin 9 and is provided with an operating handle 10. The levers 4 carrying the inking roller 1 rest by gravity on the cam 8, manually 60 operable adjusting screw 11 being provided between the levers 4 and the cam 8 and acting as an adjustable follower. By adjusting the screw 11 the gap between the inking roller 1 and the cylinder 6 can be varied. The inking roller 1 is put into or out of action by rocking the cam 65 8 by means of the handle 10.

In order to regulate and control the supply of ink to the inking zone 12 according to the present invention a means is provided for this purpose, which means comprise according to 75 Figure 1 a scraper-knife 13 and according to

Figure 2 a wiper roller 14. In the following text and for the sake of simplicity only the scraper-knife is described as the means of regulating the ink supply to the inking roller. The scraper-knife 13 is adjusted relatively to the ink roller 1 in such manner as to leave a free duct or passage for the ink. The greater the cross section of this duct or passage is, the more ink passes through and the larger the size of the ink accumulation becomes which forms between the plate cylinder 10 6 and the inking roller 1.

The scraper-knife 13 is arranged in such manner that it does not obscure the visibility of the inking zone 12, and is for example downwardly inclined in an outward direction, in order that the excess ink may flow off and be guided into the ink trough 2 by means of a gutter 15 extending into the said trough 2. The gutter 15, together with the scraper-knife 13 and the inking roller 1 form a cover for the ink trough thus preventing or tending to prevent evaporation of the ink in the said trough 2.

According to the present invention the scraper-knife 13 and consequently also the supply of ink to the inking zone 12 are mechanically controlled in such manner, that the accumulation of ink formed between the inking roller 1 and the plate cylinder 6 is completely used up when the whole of the etched plate has been inked. For this purpose the free passage or duct left for the passage of the ink between the inking roller 1 and the scraper-knife 13 is automatically varied, that is to say, the scraper-knife 13 can be adjusted towards the end of the inking operation, relatively to the inking roller 35 1 so that no ink or only very little can pass through. This displacement or adjustment of the scraper-knife 13 or the control thereof is effected by means of a cam 22, (Figures 1 and 2) which is conveniently disposed at the bottom 40 of the press but which may be mounted on any of the rotating shafts present which make one revolution during each impression. The cam 22 controls and actuates a bell crank lever 23 carrying a roller 24 which follows the contour of the cam 22. The lever 23 by means of a link or rod 25 rocks a lever 26 which in its turn rocks a cam 27, which is mounted on the fulcrum of the supporting levers 4. The cam 27 acts through the roller or follower 28 on the supporting lever 16 carrying the scraper-knife 13. 45

When the roller 24 on the lever 23 mounts the raised portion of the cam 22, the cam 27 is rocked, and consequently also the supporting lever 16 carrying the scraper-knife 13, thus allowing the normal quantity or a greater quantity than the normal quantity of ink to pass through the duct between the scraper-knife and the inking roller. When later the roller 24 runs down from the raised portion of the cam 22 to the low portion of the said cam 22 the scraper-knife 13 is again lowered towards the circumference of the inking roller 1, and the supply of ink to the inking zone is restricted, which occurs, according to the present invention at the moment, when the inking nearly reaches the end of the plate to be inked, and this restriction or cutting off of the ink supply occurs at the proper moment, so that the accumulation of ink is completely used up when the plate inking operation is finished.

The operative part of the displaceable cam 27 is arranged at or near the fulcrum of the supporting lever 4 of the inking roller 1 and near to the roller-follower 28 with the result that 70 75

when the inking roller 1 is rocked to bring it into or out of action, the distance of the roller 28 from the cam 27 is not at all or only very slightly altered.

5 In order to cut off the ink supply early or late, the cam 22 is adapted to be adjusted by moving the cam round to the required extent in order that the active part of its circumference may become operative on the roller 24 10 sooner or later as required.

The cam 22 is preferably of such a design, that the scraper-knife 13 is moved into its throttling position as quickly as possible. The result is that the accumulation of ink is used up rapidly 15 as soon as the ink supply is cut off. This enables the extension that is the "dead end" of the plate at the end of the etched part, to be reduced to a minimum.

The cam 27 controlling the scraper-knife 13 20 does not act directly on the lever 16 carrying the scraper-knife, but on the roller 28 mounted on a third arm 29 of the supporting lever 16. The roller 28 however does not lie directly on the cam 27 but is allowed a certain amount of play 25 in order to enable a stop 20 to lie against a stop-screw 21, when the scraper-knife 13 is in a position to cut off the ink supply.

The lift of the scraper-knife 13 from the inking roller can also be varied by altering the ratio 30 of transformation of the driving rods of the transmitting links or rods of the control-device. The point at which this change is effected is preferably so chosen, that during any alteration of the inking zone 12 and the ink being supplied thereto can be easily seen thus providing for the 35 change to be effected correctly and at the proper time. Consequently the alteration or adjustment is preferably effected on the lever 26 controlling the cam 27. In order to achieve this 40 a bar or link 25 is connected with the lever 26 in such manner, that its operative part is adapted to be advanced more or less towards the fulcrum 7 of the cam 27. This is attained, by adapting the connecting pin 30 so that it can be radially 45 displaced within a slot 31 provided in the lever 26, such displacement being effected by means of a manually adjustable screw 32 thus displacing the connecting pin 30 towards the fulcrum 7 of the cam 27.

50 The cam 27 is preferably mounted as near as possible to the fulcrum pin 7 of the supporting lever 4 carrying the inking roller 1, and still more preferably on the pin 7 itself, in order that the mutual positions of the roller-follower 28 55 and the cam 27 may remain constant even when the inking roller 1 is moved into or out of action.

The material used for the inking roller 1 is preferably such that it does not change as regards its diameter and that it can be easily 60 scraped and cleaned. A metallic material such as steel is particularly suitable for this purpose.

What I claim is:—

1. A process of inking a photogravure plate 65 from a fountain roller comprising maintaining an accumulation of ink at the line of cooperation between the fountain roller and the plate, applying ink progressively over the plate from said accumulation, and stopping the feed of ink to the accumulation at such an instant during the application of ink to the plate that the accumulation 70 will be used up in completing the inking of the plate.

2. A process of inking a photogravure plate 75 from a fountain roller comprising maintaining an accumulation of ink at the line of cooperation be-

tween the fountain roller and the plate, moving the printing surface of the plate progressively into contact with the ink accumulation to apply ink to said surface, and stopping the feed of the ink to the accumulation when a predetermined area of said surface has been inked, the remaining area being inked by using up the un-renewed accumulation. 5

3. In a plate-photogravure printing press, a printing plate, a fountain roller adapted to hold 10 and feed an accumulation of ink along its line of cooperation with the plate, means for moving the printing surface of the plate in contact with said ink accumulation to apply ink progressively over said surface, means for interrupting renewal 15 of said ink accumulation, and means for synchronizing passage of the end of the printing surface through said line with exhaustion of the ink accumulation consequent upon said interruption. 20

4. In a plate-photogravure printing press, a printing plate, a fountain roller adapted to maintain an accumulation of ink along its line of cooperation with said plate, means for progressively moving the printing surface of the plate through 25 said accumulation, means for controlling the layer of ink fed on said roller towards the accumulation, and means for timing the operation of the controlling means to cut off the feed of said layer at a predetermined instant before the entire 30 surface of the plate has progressed through said line whereby the rest of said surface is inked by using up the accumulation.

5. In a plate-photogravure printing press, a printing plate, a fountain roller adapted to hold 35 and feed an accumulation of ink along its line of cooperation with the plate, means for moving the printing surface of the plate in contact with said ink accumulation to apply ink progressively over said surface, means for abruptly interrupting renewal of said ink accumulation, and means for 40 synchronizing passage of the end of the printing surface through said line with exhaustion of the ink accumulation consequent upon said interruption. 45

6. In a plate-photogravure printing press, a printing plate, a fountain roller adapted to hold 50 and feed an accumulation of ink along its line of cooperation with the plate, means for varying the magnitude of the ink accumulation, means for moving the printing surface of the plate in contact with said ink accumulation to apply ink progressively over 55 said surface, means for interrupting renewal of said ink accumulation, and means for synchronizing passage of the end of the printing surface through said line with exhaustion of the ink accumulation consequent upon said interruption. 60

7. In a plate-photogravure printing press, a printing plate, a fountain roller adapted to hold 65 and feed an accumulation of ink along its line of cooperation with the plate, means for moving the printing surface of the plate in contact with said ink accumulation to apply ink progressively over said surface, means for interrupting renewal 70 of said ink accumulation, means for synchronizing passage of the end of the printing surface through said line with exhaustion of the ink accumulation consequent upon said interruption, and means for varying the instant of interruption. 75

8. In a plate-photogravure printing press, a printing plate, a fountain roller adapted to hold 75 and feed an accumulation of ink along its line of cooperation with the plate, means for moving the printing surface of the plate in contact with said ink accumulation to apply ink progressively over

said surface, a wiper cooperating with the surface of the fountain roller to control the feed of ink to the accumulation, means for moving the wiper to interrupt said feed, and means for so timing the wiper moving means as to synchronize passage of the end of the printing surface through said line with exhaustion of the ink accumulation consequent upon said interruption.

9. In a plate-photogravure printing press, a printing plate, a fountain roller adapted to hold and feed an accumulation of ink along its line of cooperation with the plate, means for moving the printing surface of the plate in contact with said ink accumulation to apply ink progressively over said surface, means for interrupting renewal of said ink accumulation, means for synchronizing passage of the end of the printing surface through said line with exhaustion of the ink accumulation consequent upon said interruption, and means for moving the fountain roller towards and away from the printing plate.

10. In a plate-photogravure printing press, a printing plate, a fountain roller adapted to hold and feed an accumulation of ink along its line of cooperation with the plate, means for moving the printing surface of the plate in contact with said ink accumulation to apply ink progressively over said surface, means for interrupting renewal of said ink accumulation, means for synchronizing passage of the end of the printing surface through said line with exhaustion of the ink accumulation consequent upon said interruption, an ink reservoir cooperating with the fountain roller, and a drip device associated with the interrupting means for returning ink to the reservoir.

11. In a plate-photogravure printing press, a printing plate, a fountain roller adapted to hold and feed an accumulation of ink along its line of cooperation with the plate, means for moving the printing surface of the plate in contact with said ink accumulation to apply ink progressively over said surface, a wiper cooperating with the surface of the fountain roller to control the feed of ink to the accumulation, means for moving the wiper to interrupt said feed, means for so timing the wiper moving means as to synchronize passage of the end of the printing surface through said line with exhaustion of the ink accumulation consequent upon said interruption, and an adjustable stop for deter-

mining the limit of approach of the wiper to the surface of the fountain roller.

12. In a plate-photogravure printing press, a printing plate, a fountain roller with a metallic surface adapted to hold and feed an accumulation of ink along its line of cooperation with the plate, means for moving the printing surface of the plate in contact with said ink accumulation to apply ink progressively over said surface, means for interrupting renewal of said ink accumulation, and means for synchronizing passage of the end of the printing surface through said line with exhaustion of the ink accumulation consequent upon said interruption.

13. A plate-photogravure printing press comprising a printing cylinder, a fountain roller capable of holding and feeding an accumulation of ink at its line of cooperation with said cylinder, a scraper knife cooperating with the fountain roller, manually operable means for adjusting the scraper knife relatively to the fountain roller, mechanically operable means for causing the knife to interrupt the feed of said ink accumulation by the fountain roller, and means for timing such interruption to occur at a predetermined instant before completion of the inking of said cylinder.

14. In a plate-photogravure printing press, a printing plate, a fountain roller adapted to hold and feed an accumulation of ink along its line of cooperation with the plate, means for automatically controlling the quantity of ink supplied to the ink supplying zone of the printing plate, lever means for carrying the inking roller, and a rockable cam arranged adjacent the fulcrum of the lever means for the ink supply.

15. A plate-photogravure printing press according to claim 14, in which the means to regulate the ink supply is mounted on the lever means.

16. A plate-photogravure printing press according to claim 14, in which the means for controlling the quantity of ink includes a plurality of rods or links which are varied manually at such a point close to the inking zone that the effect of the variation made can be observed at the inking zone while such variation is being effected.
